CLAIM

The ornamental design for a game, as shown and described.

DESCRIPTION

FIG. 1 is a top plan view of a game showing my new design; FIG. 2 is a bottom plan view of thereof; FIG. 3 is an environmental perspective view thereof; FIG. 4 is a front elevational view of FIG. 3; FIG. 5 is a rear elevational view of FIG. 3; FIG. 6 is a right side elevational view of FIG. 3, the undisclosed opposite side being a mirror image; and, FIG. 7 is an environmental perspective view, illustrating a manner of play thereof.

The broken line showing of the numbers in FIGS. 3 and 7 is for illustrative purposes only, merely disclosing numbers which can be used and how the game is played, and forms no part of the claimed design. The broken line showing of the dice is for illustrative purposes and forms no part of the claimed design.
